UNITED STATES PATENT OFFICE.

KONRAD GÖTZ, OF FURTH, GERMANY.

TOY FOR PLAYING WITH SAND.

Application filed May 15, 1926, Serial No. 109,388, and in Germany January 29, 1926.

Up to now toys for playing with sand usually consisted of a series of individual differently shaped toy parts, the number of which was in accordance with the size of the 5 toy set as a whole, and which were used by the playing child for producing the known sand cakes. Although said toys in the previously employed simple construction are instructive in a certain regard, they have the 10 drawback of stimulating the sense of forming other structures only within a certain limit, as with the toy parts present in the toy set always only the same cakes can be formed, so that said toys can not offer any 15 further incitation after longer use.

By the present invention now a toy for playing with sand is produced, which enables a greater change in the shape of the figures to be produced and accordingly 20 serves for producing figures of different shape and composed of a number of single parts. This improved toy is intended especially for flat figures, that is to say, figures, the length or (and) the breadth of which exceeds their height more or less considerably. 25 More especially, it is intended for the reproduction of animals, men, and the like, in horizontal position.

In the accompanying drawing such toys 30 are represented as employed for the reproduction of an elephant. Fig. 1 shows the outlines of an elephant composed of several individual parts, while Fig. 2 shows said parts before they are combined to the structure as a whole. Fig. 3 shows a cross-section through the toy parts with the filled-in sand. Figures 4, 5 and 6 show modifications. Such molds, which can be taken apart, have been used already for the 35 production of snow figures. In the present invention however the parts of the mold are thus shaped, that various figures can be represented by the transposition of individual mold parts or by the employment of further 40 mold parts respectively. For instance the elephant represented in Fig. 1 which is composed of the head portion *a*, the body portion *b*, the rear portion *c*, and the leg portions *d* and *e*, which all are shown separated 45 in Fig. 2. Any one of these portions may be replaced by another one having another shape or (and) size. Thus, for instance, 50 the elephant can be transformed into a

hippopotamus (Fig. 4) by the removal of the head portion *a* and the rear portion *c* 55 of the elephant (Figs. 1 and 2) and substituting therefor portions *l* and *m*, as shown in Fig. 4. Of course, also the body portion, as well as the leg portions, may be replaced by another body portion and by other leg 60 portions of whatever shape and size whereby children using the toy may be kept constantly amused and interested by not only building animal or other figures known to them but also by the use of their imagination in conjuring and composing figures of 65 phantastic shapes. This is true of toy portions for the production of animals, as well as for the production of other animal objects, for instance representations of human 70 beings, as in Figs. 5 and 6, which are composed of a body portion *f*, arm portions *h*, leg portions *g*, and a head portion *i* (Fig. 5) or *k* (Fig. 6). All these portions may be 75 replaced by other ones of other shapes or (and) sizes, and even portions of human beings and of animals may be combined with each other according to the phantasy of a child on the one hand and the number of portions available on the other hand. 80

I claim:

1. A toy sand mold comprising sections adapted when assembled to form a figure and to provide a mold presenting a flat reverse side and a convex obverse side, the 85 walls of the convex side delineating a mold cavity opening through the reverse side and shaped to produce in the surface of a body of sand a surface configuration in elevation of the outlined figure, said sections having 90 meeting surfaces and adapted for interchangeable use with other sections to change the form of the figure.

2. A toy sand mold comprising sections simulating portions of an animal or other 95 figure and adapted to be assembled to produce an image of the figure in relief, each section having a convex obverse side and flat reverse side, the walls of the convex sides of the sections delineating cavities communicating with each other and collectively forming a mold chamber opening through the flat side of the mold, the sections having 100 transverse abutment surfaces.

In testimony whereof I affix my signature.

KONRAD GÖTZ.
